UNITED STATES PATENT OFFICE.

WALTER D. TEAGUE, OF NEW YORK, N. Y., ASSIGNOR TO NATIONAL CARBON COMPANY, INC., A CORPORATION OF NEW YORK.

DESIGN FOR A COMBINED SUPPORT AND HOUSING FOR AN ELECTRIC ARC LAMP.

Application filed October 8, 1928. Serial No. 28,395. Term of patent 14 years.

To all whom it may concern:

Be it known that I, WALTER D. TEAGUE, a citizen of the United States, residing at New York city, in the county and State of New York, have invented a new, original, and ornamental Design for a Combined Support and Housing for an Electric Arc Lamp, of which the following is a specification, reference being had to the accompanying drawings, forming part thereof, and wherein Fig-

ure 1 is a perspective view of the support and housing taken from the side, Figure 2 is a similar view from the front, and Figure 3 is a plan view of the top of the housing.

I claim:

The ornamental design for a combined support and housing for an electric arc lamp substantially as shown.

WALTER D. TEAGUE.
